(57) **CLAIM**

The ornamental design for a computing device display screen with graphical user interface for a food rating and display system, as shown and described.

DESCRIPTION

The sole FIGURE is a front view of the computing device display screen with graphical user interface for a food rating and display system showing the new design.

The broken line showing of an electronic device and a display screen with graphical user interface is included for the purpose of showing portions of the article which form no part of the claimed design.
